UNITED STATES PATENT OFFICE

151,460

DESIGN FOR A BOTTLE

Jean Bourges Mayfield, New York, N. Y., assignor to Joseph S. Lindemann, New York, N. Y.

Application August 13, 1946, Serial No. 132,484

Term of patent 14 years

(Cl. D58—9)

To all whom it may concern:

Be it known that I, Jean Bourges Mayfield, a citizen of the United States, residing at New York city, in the county of New York and State of New York, have invented a new, original, and ornamental Design for a Bottle, of which the following is a specification, reference being had to the accompanying drawing, forming part thereof.

In the drawing:

Fig. 1 is a front elevational view of a bottle, showing my new design;

Fig. 2 is a side elevational view thereof; and
Fig. 3 is a bottom plan view thereof.

I claim:

The ornamental design for a bottle, substantially as shown.

JEAN BOURGES MAYFIELD.
